(57) **CLAIM**

The ornamental design for a tie and pocket decoration holder, as shown and described.

DESCRIPTION

FIG. 1 is a front elevational view of a first embodiment of a tie and pocket decoration holder showing my design therefor, the pocket decoration being shown as environment only and forming no part of the design;

FIG. 2 is a rear elevational view thereof, the pocket decoration being shown as environment only and forming no part of the design;

FIG. 3 is a side elevational view thereof with the top opened for insertion of a pocket ornament, the opposite side being identical;

FIG. 4 is a top plan elevational view thereof with the top closed;

FIG. 5 is a bottom plan view thereof;

FIG. 6 is a front elevational view of a second embodiment of the tie and pocket decoration holder showing my new design therefor, the pocket decoration being shown as environment only and forming no part of the design;

FIG. 7 is a rear elevational view thereof, the sides, top and bottom being identical to respective FIGS. 3, 4 and 5; and,

FIG. 8 is a front elevational view showing a tie and pocket decoration holder in accordance with my design with a tie and pocket decoration shown as environment only and forming no part of the design.

The broken lines in the drawings depict environmental subject matter only and form no part of the claimed design.
